ABSTRACT OF THE DISCLOSURE

Wear resistant members, especially suitable for defining a coin passage of a coin counting and (or) sorting machine are made of supporting members and a wear resistance surface made of ceramics or cermet and bonded to supporting members. The wear resistant surface is divided into a plurality of segments to prevent deformation or cracking.

BACKGROUND OF THE INVENTION

This invention relates to wear resistant members in the form of plates or bars, and more particularly to such members especially suitable for defining coin passages of coin counting and (or) sorting machines.

There are many applications which are required to employ highly wear resistant component parts. For example, in one type of a coin counting and sorting machine, various types of coins having different diameters are passed through a coin passage of adjustable width during which coins having smaller diameters than that of a coin of predetermined type are dropped, and only those of the predetermined type are counted, accumulated and packed. Such a coin passage is ordinarily defined by a pair of spaced apart adjustable bars, guide plates located at the inlet and exit ends of the coin passage, and guide means to guide coins to move into the passage. These component members are required to be highly wear resistant to resist large frictional and abrasive actions of coins. As wear resistant materials, ceramics or cermet are known. Although these materials are extremely hard and wear resistant, it is difficult to obtain thin and relatively wide sheets thereof because of their brittleness. When one tries to provide a wear resistant plate by bonding a thin sheet of ceramic or cermet material to a supporting plate of high mechanical strength such as a steel plate, and then machine the surface of the thin sheet, the thin sheet tends to deform or crack.

SUMMARY OF THE INVENTION

Accordingly, it is the principal object of this invention to provide an improved wear resistant plate which does not deform or crack.

The wear resistant plate embodying this invention comprises a supporting plate and a thin sheet of wear resistant material bonded to one surface of the supporting plate. The thin sheet comprises a plurality of segments of ceramic material or cermet. Since the surface area of each segment can be made relatively small, the tendency of deformation or cracking can be avoided.

2**BRIEF DESCRIPTION OF THE DRAWING**

- In the accompanying drawing:
- FIG. 1 shows a plan view of a wear resistant plate embodying this invention;
- 5 FIG. 2 is a sectional view taken along line 2—2 in FIG. 1;
- FIG. 3 shows a section of a modified embodiment;
- FIG. 4 is a plan view of a coin passage of a coin counting and sorting machine utilizing wear resistant members of this invention;
- 10 FIG. 5 shows a section taken along line 5—5 in FIG. 4;
- FIG. 6 shows a plan view of a left-hand guide plate;
- FIG. 7 shows a section of the guide plate taken along a line 7—7 in FIG. 6;
- 15 FIG. 8 is a plan view of a left hand guide bar;
- FIG. 9 shows a section through a line 9—9 in FIG. 8;
- FIG. 10 shows a plan view of a guide plate on the inlet side of the coin passage;
- 20 FIG. 11 shows a section of the guide plate taken along a line 11—11 in FIG. 10;
- FIG. 12 is a plan view of an adjusting plate associated with the right hand guide bar;
- FIG. 13 is a sectional view of the adjusting plate taken along a line 13—13 in FIG. 12;
- 25 FIG. 14 is a side view of a guide plate on the exit side of the coin passage; and
- FIG. 15 is a sectional view of the guide plate taken along a line 15—15 in FIG. 14.
- 30 **DESCRIPTION OF PREFERRED EMBODIMENT**
- Referring now to FIGS. 1 and 2 illustrating one embodiment of a novel wear resistant plate 50 especially suitable for use as a guide plate of a coin counting and sorting machine, the wear resistant plate 50 comprises
- 35 a supporting plate of metal 51 and a thin flat sheet of ceramics or cermet 52 which is divided into a plurality of segments or pieces. These pieces are received in a recess 53 on the upper surface of the supporting plate and bonded thereto by a suitable binder such as a resin.
- 40 The lower surface of the ceramic or cermet sheet is ground and polished to provide a flat and smooth surface flush with the upper surface of supporting plate 51. While in the embodiment shown, the ceramic or cermet sheet is divided laterally, it is to be understood that it can be divided in any desired manner according to the dimensions and configuration of the sheet. Openings 54 are provided on the opposite sides of the supporting plate to receive screws and the like (not shown).
- 45 Examples of ceramic materials which may be used are sintered bodies of high purity alumina, borides, chromium oxides and zirconium oxides, and as the cermet material, use may be made of sintered bodies essentially consisting of high purity tungsten carbides and titanium carbides.
- 50 In this manner, as the wear resistant surface is comprised by a plurality of segments of ceramic or cermet material bonded to the supporting plate and the surface area of each segment can be made comparatively smaller than the total area of the wear resistant surface. As is well known in the art, although these sintered materials are very hard and wear resistant, owing to their brittleness, it is difficult to prepare thin and flat sheets thereof of wide surface area. However, according to this invention, as a number of small segments are bonded side-

by-side to form a wear resistant plate of the desired area, the difficulty referred to above can be readily obviated.

In a modified construction shown in FIG. 3 the thickness of the supporting plate 51 is increased at portions just beneath divided ceramic or cermet segments 52 to increase the mechanical strength. When machined to thin gauge, ceramic or cermet segments have a tendency to be deformed by about 0.02 to 0.03 mm. and such deformation is further increased when such segments are bonded to the supporting plate having defects such as surface irregularity or warp, thus causing cracking or peeling off of the segments. Increased thickness at portion 55 which is formed with a recess 53 to receive wear resistant segments increases the mechanical strength of that portion or that of the assembly of the supporting plate and wear resistant segments, so that deformation of these segments at the time of machining thereof can be eliminated or minimized. Moreover, the thickened portion effectively absorbs residual stress created at the time of bonding of the wear resistant segments or small vibrations at the time of use of the wear resistant plate thereby to decrease adverse effects upon the ceramic or cermet segments and thus effectively prevents cracking or peeling off thereof.

While the novel wear resistant plate can be used in any application requiring durability, the above described embodiments are especially suitable to form a passage or chute to guide and or sort various types of coins in coin counting and (or) sorting machines.

FIGS. 4 through 15 illustrate one example of such application. In the coin counting and sorting machine illustrated, coins disposed on a horizontal rotary disc 60 are thrown into a coin passage 28 extending in the radial direction of the rotary disc and defined by a pair of spaced apart guide bars 1 and 2, a guide plate 3, an adjusting plate 4, a guide plate 5 on the inlet side and a guide plate 6 on the exit side of the coin passage.

As shown in FIGS. 4, 10, and 11, guide plate 5 on the inlet side is disposed adjacent the periphery of the rotary disc to receive coins therefrom and is provided with a recess 7 extending in the direction of movement of coins and having a width wider than the diameter of the largest coin to be processed. Similar to the embodiment shown in FIGS. 1 and 2, thin segments of ceramic or cermet 8 are fitted in recess 7 and are bonded to guide plate 5 by any bonding agent such as a resin.

One edge of the guide plate 5 and ceramic or cermet segments 8 which faces the periphery of rotary disc 60 is slanted as at 9.

As shown in FIGS. 9 and 10, the left side guide bar 1 is provided with a notch 10 in its right upper edge to receive a bar 11 of ceramics or cermet. Guide bar 1 is secured on a machine frame 18 with its front edge (upper edge as viewed in FIG. 9) abutted against the rear edge of guide plate 5, and with the upper surface of the ceramic bar 11 flush with the upper surface of ceramic segments 8.

As shown in FIGS. 6 and 7, the left side guide plate 3 has a bar 12 of ceramics or cermet 12 bonded to the right hand edge thereof and is secured on the upper surfaces of guide plates and guide bar 1 as shown in FIG. 5. Guide bar 1 and guide plate 3 on the left hand side are secured in position by means of screws 17 extending through openings 13 and 14. The width of guide plate 3 is made narrower than that of guide bar 1 to expose a portion of the upper surface of ceramic bar 11.

Right hand guide bar 2 is secured to machine frame 18 through a movable frame 19 so that the spacing between guide bars 1 and 2 may be adjustable. Guide bar 2 is constructed symmetrically with guide bar 1 and has a ceramic bar 21 bonded to a notch 20 on the left upper edge thereof. As shown in FIGS. 12 and 13, an adjusting plate 4 has a ceramic bar 22 bonded to its inner edge and another ceramic piece 24 bonded to its inlet end, with the ceramic piece 24 having an arcuate guide edge 23.

Adjusting plate 4 is mounted upon guide bar 2 and the plate and bar are secured to a movable frame 19 by screws 27 extending through openings 25. As shown in FIG. 5, a portion of the upper surface of ceramic bar 22 is left exposed to provide a coin sliding surface. A cover plate 26 is mounted on the adjusting plate 24 by means of screws 27a, with the inner edge of cover plate 26 projecting inwardly beyond that of adjusting plate 4. Between guide bar 2 and cover plate 26, there is defined a gap sufficient to pass the peripheral portion of one coin. A guide plate 6 is secured to machine frame 18 by means of a screw 29 on the exit end of coin passage or gap 28 formed between guide bars 1 and 2. As best shown in FIGS. 14 and 15, guide plate 6 is provided with a notch 30 to receive a segment or segments of ceramics or cermet 31 which are bonded to guide plate 6 in any suitable manner. The upper surface of ceramic segments on which coins slide is finished flush with that of guide plate 6. A guide member 34 having a concave guide surface 33 which cooperates with said arcuate guide edge 23 to form a coin guide passage is mounted upon the inlet end of the left hand guide plate 3 by screws 35. Further, a conveyor belt 36 is passed around a pair of pulleys 37 and 38 respectively above guide plates 5 and 6 so that the lower run of the belt moves downwardly, as viewed in FIG. 4, to carry therewith coins which are brought against concave guide surface 33 by the rotation of the rotary disc into coin passage 38. A suitable counting mechanism including a star wheel 39 is provided on one side of the coin passage adjacent guide plate 6 on the exit end to count the number of coins that have passed through coin passage 28.

Although not shown in the drawing, adjusting plate 4 is biased to move away from the coin passage, and the width of the coin passage is adjusted by a polygonal cam 40 cooperating with the adjusting plate 10 according to the diameter or type of the coin to be selected.

Each one of bars 11, 12, 21 and 22 and segments 8 and 31 may be a single piece or divided pieces depending upon its configuration and dimensions.

In operation, the rotary disc 60 is rotated in the clockwise direction as viewed in FIG. 4 so that coins mounted thereon are moved to its periphery by centrifugal force. When caught by the concave guide surface 33, coins are thrown outwardly into the coin guide passage between concave surface 37 and arcuate guide edge 23 and thence onto the guide plate 5 on the inlet side. Coins are then carried by the conveyor belt along ceramic bars 11 and 21 of guide bars 1 and 2 and between ceramic bars 12 and 22. Coins having diameters smaller than the diameter of the coin to be sorted fall down through coin passage 28. Coins moved along ceramic bars 11 and 21 are then conveyed onto guide plate 6 on the exit end, and, after operating star wheel 39 of the counting mechanism, they are piled up in a packing mechanism (not shown).

As segments and bars defining the coin passage are made of ceramic or cermet material, wear thereof can be reduced greatly, and an accurate gap can be maintained over a long period without the necessity of exchanging worn out parts, thus increasing the sorting efficiency of coins.

While the invention has been described in terms of preferred embodiments, thereof it will be obvious to those skilled in the art that this invention is not limited to these particular embodiments and that many changes and modifications may be made without departing from the spirit and scope of the invention as defined in the appended claims.

What is claimed is:

1. A wear resistant plate comprising a supporting plate of metal and a wear resistant sheet bonded to one surface of said supporting plate, said wear resistant sheet comprising a plurality of segments arranged side by side and

made of a member selected from the group consisting of ceramic material and cermet material.

2. The wear resistant plate according to claim 1 wherein said supporting plate is provided with a shallow recess, and said wear resistant sheet is received in said recess and machined flush with said supporting plate.

3. The wear resistant plate according to claim 1 wherein the thickness of the portions of said supporting plate underlying said wear resistant sheet is increased.

4. The wear resistant plate according to claim 1 wherein said ceramic material is a member selected from the group consisting of sintered alumina, borides, chromium oxides and zirconium oxide.

5. The wear resistant plate according to claim 1 wherein said cermet material is a member selected from the group consisting of a sintered body essentially consisting of high purity tungsten carbide and sintered body of titanium carbide.
